UNITED STATES PATENT OFFICE.

JOSEPH SCHMITZ, OF PHILADELPHIA, PENNSYLVANIA, ASSIGNOR TO UNIFORM DYEING MACHINE CO., OF GROVEVILLE, NEW JERSEY, A CORPORATION OF NEW JERSEY.

PROCESS OF DYEING.

1,160,001.

Specification of Letters Patent.

Patented Nov. 9, 1915.

Application filed June 13, 1914. Serial No. 844,927.

To all whom it may concern:

Be it known that I, JOSEPH SCHMITZ, a citizen of the United States, residing in Philadelphia, Pennsylvania, have invented 5 certain Improvements in the Process of Dyeing, of which the following is a specification.

The object of my invention is to dye raw cotton and like material as it comes from 10 the bale in such a manner that it will be evenly dyed throughout. This object I attain in the following manner, reference being had to the accompanying drawings, in which:

15 Figure 1 is a perspective view of a bale of cotton, showing the first step in the process; Fig. 2 is a perspective view of the rolled section of the cotton prior to being placed in the dye vat; Fig. 3 is a sectional plan view 20 on the line *a—a*, Fig. 4, of one form of dye vat showing the rolled sections in position; Fig. 4 is a transverse sectional view on the line *b—b*, of Fig. 3; and Fig. 5 is a detached perspective view of one of the tubes 25 used in the rolls of cotton at the center of the vat.

It is exceedingly difficult to properly dye raw cotton. The usual practice is to pull 30 the cotton from the bale and to pack it in a vat, generally under pressure, and to subject it to the dye liquor while under pressure. The dyeing is not always uniform and a certain percentage of the cotton has to be discarded on that account.

35 By my invention, I am enabled to evenly dye raw cotton by making it into rolls or bats, packing the cotton in a vat and circulating the dye liquor through the material first in one direction and then in another direction. I find that the cotton in a 40 bale can be removed in thin layers and I utilize this knowledge and roll the cotton, one layer after another, as indicated in Fig. 1 of the drawings. When a roll is completed it is in the shape illustrated in Fig. 45

2. The rolls are placed on end in a vat, as illustrated in Figs. 3 and 4.

The vat has a casing 1 and a transverse partition 2 which separates the dyeing chamber 3 from the mixing or circulating chamber 4. Within the dyeing chamber is a 50 perforated partition 5, some distance from the bottom, and the bottom chamber has a perforated pipe 6 which communicates with

a circulating pipe 7 connected to any suitable circulating pump.

8 is a circulating pipe communicating with the chamber 4 and with a circulating pump. Suitable valves may be provided for reversing the circulation so that the dye liquor 60 may pass up through the dyeing chamber and down through the circulating chamber or vice versa.

The rolls or bats *x* of cotton are packed on end on the perforated partition 5 and 65 tubes 9 are placed in the central rolls, as indicated in Fig. 3. These tubes are preferably made as shown in Fig. 5, with a vertical slot 10 and a perforated upper end 11. The lower end of the tube is open to allow 70 the dye liquor to circulate into the tube through its slot and into the roll of cotton.

In order to properly hold the cotton on to the lower perforated partition 5, I provide a perforated partition or cover plate 12 75 and this is fastened by any suitable means. The tubes 9 are preferably shorter than the rolls so that the cotton will extend over the ends of the tubes, as shown in Fig. 4, thus preventing the dye liquor from short circuiting. When the perforated plate 12 is in position and firmly secured the dye liquor first passes into the chamber 4 and then flows over the partition 2, which is lower than the side walls of the vat, then into the 85 dyeing chamber, passing down through the body of cotton and out through the pipe 7 at the bottom of the dyeing chamber. After the dye liquor has circulated for a given length of time in this direction, suitable 90 valves are adjusted so as to cause the circulation of the liquor to be reversed so that the liquor will flow through the pipe 7, distributing pipe 6, up through the perforated partition 5, through the rolls of cotton and 95 through the tubes, and it will flow over the short partition 2 into the circulating chamber 4.

The partition 5 is preferably made in sections and rests on ledges 13 projecting from 100 the sides of the vat and the cover plate 12 is also made in sections and is held in position by any suitable fastenings. In the present instance, these fastenings are in the form of angle bars 14, Fig. 3, secured to the side 105 walls of the vat by bolts, and bars 15 extend across the vat and hold the central portion of the sections in place. In the present in-

stance, these bars 15 extend under pins 15^a at each side of the vat, as shown clearly in Figs. 3 and 4.

It will be understood that other types of dyeing apparatus may be used where the liquor is circulated first in one direction and then in the opposite direction, and my improved process can be carried out in an apparatus in which the circulation is in one direction only. I have found, however, that the best results are obtained where the circulation is reversed at intervals.

I claim:

1. The process herein described of dyeing raw cotton, said process consisting in rolling a section of the cotton into small bats, placing the bats on end in a vat, then circulating the dye liquor through the bats.

2. The process herein described of dyeing raw cotton, said process consisting in rolling sections of the cotton into small bats, placing these sections on end in a vat having a perforated bottom and placing a perforated cover over the bats, circulating the

dye liquor first in one direction and then 25 in the opposite direction through the rolls or bats of cotton so as to thoroughly impregnate and evenly dye the said cotton.

3. The process herein described of dyeing raw cotton, said process consisting in rolling 30 cotton into small bats, placing a circulating tube in some of said bats, closely packing the several bats in a dye vat having a perforated bottom, locating the bats, with the circulating tubes therein, at the center of 35 the vat, and placing a perforated cover over the bats, then allowing the dye liquor to circulate vertically through the bats, first in one direction and then in the opposite direction.

In testimony whereof, I have signed my name to this specification, in the presence of two subscribing witnesses.

JOSEPH SCHMITZ.
